(57) **CLAIM**

The ornamental design for an excavator bucket, as substantially shown and described.

DESCRIPTION

FIG. 1 is a back view of the excavator bucket of the present invention;

FIG. 2 is a front view of the excavator bucket of the present invention;

FIG. 3 is a bottom view of the excavator bucket of the present invention;

FIG. 4 is a top view of the excavator bucket of the present invention;

FIG. 5 is a left side view of the excavator bucket of the present invention;

FIG. 6 is a right side view of the excavator bucket of the present invention;

FIG. 7 is a top front perspective view of the excavator bucket of the present invention;

FIG. 8 is a bottom front perspective view of the excavator bucket of the present invention;

FIG. 9 is a top rear perspective view of the excavator bucket of the present invention; and,

FIG. 10 is a bottom rear perspective view of the excavator bucket of the present invention.
